CLAIM

The ornamental design for a shoe as shown and described.

DESCRIPTION

FIG. 1 is a front left perspective view of a shoe showing our new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1;

FIG. 7 is a bottom view of the design shown in FIG. 1;

FIG. 8 is front left perspective view of a second embodiment of a shoe showing our new design;

FIG. 9 is front view of the design shown in FIG. 8;

FIG. 10 is a rear view of the design shown in FIG. 8;

FIG. 11 is a right side view of the design shown in FIG. 8;

FIG. 12 is a left side view of the design shown in FIG. 8;

FIG. 13 is a top view of the design shown in FIG. 8; and,

FIG. 14 is a bottom view of the design shown in FIG. 8.

The dashed lines in the Figures represent stitching seams of the design. Moreover, the material shading of the embodiments shown in FIGS. 8-14 represents a knitted textile that forms part of the claimed design.

1 Claim, 14 Drawing Sheets
